To all whom it may concern:

Be it known that we, Robert Eckhardt, Paul Henrici, and Adolf Gross, a citizen of Germany and resident of Am Damm 72a, Leun (Lahn), Germany; a citizen of Germany and resident of Morgenweide 2, Wetzlar, Germany; a citizen of Germany and resident of Silhöfertstrasse 12, Wetzlar, Germany, respectively, have invented a new, original, and ornamental Design for a Camera Carrying Case, of which the following is a specification, reference being had to the accompanying drawing, forming a part hereof.

Fig. 1 is a front elevational view of a camera carrying case, showing our new design;

Fig. 2 is a rear elevational view thereof;

Fig. 3 is a side elevational view thereof.

The strap is shown broken away in Figs. 1 and 2 for convenience of illustration.

The side of the case not shown is the same as the side shown.

The dominant feature of our design resides in the portions shown in full lines.

We claim:

The ornamental design for a camera carrying case, as shown and described.
